UNITED STATES PATENT OFFICE.

WINFRED MUDGE BROOKS, OF EAST ORANGE, NEW JERSEY, ASSIGNOR TO E. J. BROOKS & CO., OF NEW YORK, N. Y., A CORPORATION OF NEW YORK.

SELF-LOCKING SEAL.

1,137,183.

Specification of Letters Patent.

Patented Apr. 27, 1915.

Application filed December 18, 1914. Serial No. 877,984.

To all whom it may concern:

Be it known that I, WINFRED MUDGE BROOKS, a citizen of the United States of America, and a resident of East Orange, in the State of New Jersey, have invented a new and useful Improvement in Self-Locking Seals, of which the following is a specification.

This invention relates to metallic seals for securing the doors of railway freight cars and warehouses, so as to prevent pilfering without detection, and for other analogous purposes as for securely attaching license tags and like identification devices so as to prevent tampering therewith.

It relates more particularly to self-fastening or self-locking seals, which dispense with the use of seal presses, and to sealing shackles made from wire.

The present invention consists in a self-locking seal of a new type, and certain novel functional features thereof as hereinafter particularly described and claimed.

The leading object of the invention is the production of a secure self-locking seal from wire.

Other objects will be set forth in the general description which follows.

Two sheets of drawings accompany this specification as part thereof.

Figure 1 is a face view of one of my said seals as it leaves the factory and as suspended preliminarily in serially numbered bunches from a stringing wire; Fig. 2 represents a section on the line A—B, Fig. 1; Fig. 3 is a face view of the same seal applied to car-door staples, and self-locked; Fig. 4 represents a section on the line C—D, Fig. 3; Figs. 5, 6 and 7 are face views of additional species of the same invention as they leave the factory and as carried by a sealer; Fig. 8 is a face view of another of the improved seals as it leaves the factory, provided with an inseparable tag of embossed sheet metal; Fig. 9 represents a cross section on the line E—F, Fig. 8; Fig. 10 is a fragmentary face view of a modified seal and tag; and Figs. 11 and 12 are fragmentary perspective views illustrating the production of the improved seal from square or triangular wire.

Like reference characters refer to like parts in all the figures.

The improved self-locking seal, in any of its forms or species, has a pair of interlock-

ing portions 1 and 2 adjoining the respective ends of a main loop portion 3, and is self-locked by wrapping said portion 1 tightly around said portion 2, a single coil as shown at *a* in Figs. 3 and 4 being sufficient; forming such locking coil *a* is rendered easy, opening the same without breaking the wire is prevented, and the detection of any tampering with the seal is insured by means of transverse "grooves" or notches 60 4 in that side of said portion 1 which becomes innermost in said coil *a*; and the endwise withdrawal of said portion 2 from within said coil *a* is prevented by a stop portion 5 or 5^a or 5^b or 5^c or 5^d of the same piece 65 70 of wire.

The piece of wire may be cut from a continuous length of ordinary iron or brass or copper wire of suitable gage, round in cross section as represented in Figs. 1 to 10 inclusive, square as represented by Fig. 11 or triangular as represented by Fig. 12. Ordinary round iron wire annealed soft answers every purpose.

The notches 4 are intended to be cut in a 80 suitable machine so as to be of uniform depth, and so that the displaced metal elongates the wire. The back of the portion 1 is thus stretched and rendered harder but, bending at all the notches simultaneously for 85 the most part in the locking operation, it readily yields sufficiently for that movement without liability to break. The tendency of any unlocking movement is to bend the metal of the hardened back of the wire at the 90 outermost notch, then at the second and so on; and the metal invariably breaks at one of the first notches, before unlocking can be effected.

In the several species represented by Figs. 95 1 to 4 inclusive, Fig. 5, Fig. 6 and Fig. 7, the improved seal is further provided with a flattened number-bearing portion 6 in continuation of said portion 1, so as to be conveniently numbered in series as represented 100 by "222 222" "222 223" and "222 224" in Figs. 1, 5, 6 and 7, respectively. It is customary to temporarily string seals so numbered on looped wires in bunches of one hundred consecutively numbered seals. A 105 looped wire for that purpose is represented in dotted lines at 7 in Fig. 1.

In the species represented by Figs. 1 to 4 inclusive, said withdrawal preventing portion 5 is in the form of a coil similar to said 110

locking coil *a*, so as to be of ample size to prevent withdrawal of the interlocking portion 2 through said coil *a*, should the latter fail to close properly around said portion 2, 5 and so as to be self-guarded against being opened by internal notches 4' similar to the aforesaid notches 4. Said coil-shaped withdrawal preventing portion 5 serves also as means for temporarily stringing such seals 10 on said wire 7.

Distinct from the withdrawal preventing portion, 5, in this species, the improved seal is further constructed with a flattened mark-bearing portion, 8, the specific mark "R. R." 15 representing the initials of a railroad stamped in the metal.

In the species represented by Fig. 5, the aforesaid withdrawal preventing portion 5^a is flattened like said portion 8 and provided 20 with a like stamped mark "R. R." and provision is made for stringing the seal by a loop-forming coil 9 interposed between the notched portion 1 and the number-bearing portion 6. Said coil 9, so arranged serves 25 also to form an effective thumb rest for use in forming the locking coil (*a*, Fig. 4) by wrapping the notched portion 1 around the interlocking portion 2 of the seal.

In the species represented by Fig. 6, the aforesaid withdrawal preventing device 5^b 30 is also a flattened portion provided with a like stamped mark "R R," and is provided with a hole 10 for use in stringing the seal on the wire 7.

In the species represented by Fig. 7, the improved seal, generically considered, is provided with a coating of suitable paint or the like to give it any desired characteristic color, represented by horizontal shade lines 35 at 11. This provision may be in addition to said marks represented by "222 224" and "R R" or as a substitute for such marks or either of them. In applying such coloring the seals are dipped into liquid paint or the like and dried as the last stages of manufacture.

The metal may if desired be bright cleaned or, if iron, coppered so that the color will show up better as the distinguishing mark of 50 the seal. Fig. 7 also illustrates the omission of separate means for stringing the seal on said wire 7; the main loop 3 being available for this purpose, but less secure against the accidental escape of seals from the stringing 55 wire than is desirable.

In the species represented by Figs. 8 and 9, the improved seal, generically considered, is provided with a sheet-metal tag 12 on an extension 1' of the body wire of the seal, between swaged stop portions 13, 14, to carry 60 more distinct embossed serial numbers, represented by "1002" in the figure. Such tag may conveniently be stamped with any other required marks, represented by "XXXNY" 65 and "License" in the figure; and the with-

drawal preventing portion 5^d may be blank and of any convenient form. A flattened extremity similar in this respect to said portions 5^a, 5^b and 5^c is represented. The tag 12 is attached by rounded ends 15, Fig. 9, ap- 70 75 pertured and bent at right angles.

In the modification represented by Fig. 10, the apertured ends 15' of an otherwise similar sheet-metal tag 12' are flattened and engage with flattened stop portions 13' 14' so 75 as to keep the tag from turning on the extension 1' of the body wire of the seal, supposing the latter to be round in cross section.

With the square wire, Fig. 11, or triangular wire, Fig. 12, apertures fitted to the wire 80 would obviously suffice in such tags 12, 12'; and other like modifications will suggest themselves to those skilled in the art.

The improved seal in any of the species leaves the factory and is carried by the 85 sealer in the form represented by Figs. 1 and 2, Fig. 5, Fig. 6, Fig. 7 and Fig. 8, respectively, and, after passing either end through a pair of car-door staples 16, 17, Fig. 3, or the like, the notched locking portion 1 is 90 wrapped by hand around the interlocking portion 2, which is accomplished in an instant, without the aid of a seal press, and completes the self-locking or sealing operation. It will be understood that in all the 95 species, the portions 1 and 2 are interlocked in one and the same manner, and appear when locked as shown at *a* in Figs. 3 and 4; and in all the species, so locking the seal is 100 facilitated, and tampering with the seal is detected by means of the notches 4 in the manner above described.

Having thus described said improvement, I claim as my invention, and desire to patent under this specification: 105

1. A self-locking seal having two interlocking portions one of which is adapted to be wrapped around the other to form a locking coil, means for insuring the fracture of said coil by a reverse movement thereof, a 110 loop the ends of which inseparably adjoin said interlocking portions respectively and means for preventing the withdrawal of the innermost of said interlocking portions.

2. A self-locking seal having two interlocking portions one of which is adapted to be wrapped around the other to form a locking coil, means for insuring the fracture of said coil by a reverse movement thereof, a 115 loop the ends of which inseparably adjoin said interlocking portions respectively, and a coil-shaped withdrawal preventing portion inseparably adjoining the outer end of the innermost of said interlocking portions.

3. A self-locking seal having two interlocking portions one of which is adapted to be wrapped around the other to form a locking coil, means for insuring the fracture of said locking coil by a reverse movement thereof, a loop the ends of which insepara- 120 125 130

bly adjoin said interlocking portions respectively, and a coil-shaped withdrawal preventing portion inseparably adjoining the outer end of the innermost of said interlocking portions and means for insuring the fracture of said withdrawal preventing coil by a reverse movement thereof.

4. A self-locking seal having two interlocking portions one of which is adapted to be wrapped around the other to form a locking coil, means for insuring the fracture of said locking-coil by a reverse movement thereof, a loop the ends of which inseparably adjoin the said interlocking portions respectively and a coil-shaped withdrawal preventing portion adjoining the outer end of the innermost of said interlocking portions and provided with internal notches adapted to insure its fracture by an attempt

20 to uncoil it.

5. A self-locking seal having two interlocking portions one of which is adapted to be wrapped around the other to form a locking coil, a loop the ends of which inseparably adjoin said interlocking parts respectively, a withdrawal preventing coil near the extremity of the innermost of said interlocking portions and transverse weakening notches on the inner sides of each of said locking and withdrawal preventing coils adapted to assure the fracture of said coils by a reverse movement thereof, the metal at the outer side of said coils being hardened and made brittle.

35 6. A self-locking seal having two inter-

locking portions one of which is adapted to be coiled around the other to lock the seal, notches on the inner side of the locking coil so formed, adapted to prevent uncoiling without fracture of said coil, a loop the ends 40 of which inseparably adjoin said interlocking portions and a withdrawal preventing portion inseparably adjoining one end of the innermost of said interlocking portions.

7. A self-locking seal having two interlocking portions one of which is adapted to be coiled around the other to lock the seal, notches on the inner side of the locking coil so formed, adapted to prevent uncoiling without fracture of said coil, a loop the ends 45 50 of which inseparably adjoin said interlocking portions and a coil shaped withdrawal preventing portion adjoining one end of the inner of said interlocking portions.

8. A self-locking seal having two interlocking portions one of which is adapted to be coiled around the other to lock the seal, notches on the inner side of the locking coil so formed, adapted to prevent uncoiling without fracture of said coil, a loop the ends 55 60 of which inseparably adjoin said interlocking portions and a coil shaped withdrawal preventing coil similarly notched on its inner side integral with the innermost of said interlocking portions.
